UNITED STATES PATENT OFFICE.

PRIMUS W. SMITH AND JOHN J. BOOKHOUT, OF DALLAS, TEXAS.

BLADE FOR WELL-DRILLING DEVICES.

1,426,681.

Specification of Letters Patent. Patented Aug. 22, 1922.

Application filed March 21, 1921. Serial No. 454,152.

To all whom it may concern:

Be it known that we, PRIMUS W. SMITH and JOHN J. BOOKHOUT, citizens of the United States, residing at Dallas, in the county of Dallas and State of Texas, have invented certain new and useful Improvements in Blades for Well-Drilling Devices, of which the following is a specification.

This invention relates to new and useful improvements in blades for well drilling devices.

The subject matter of the present invention is shown in the application maturing into Letters Patent #1,370,492, issued to us under date of March 1, 1921, but not claimed therein.

The object of the invention is to provide a drilling or cutting blade having certain characteristics which make it superior and more efficient when used with the drilling device described in the foregoing Letters Patent No. 1,370,492. A particular object of the invention is to provide a cutting blade which may be securely clamped in a well drilling device and readily removed therefrom when desired. A further object is to give the cutting blade a sufficient bearing on its support as to adequately sustain it under various drilling conditions and to cause it to give a maximum service. An important advantage of the invention results from a structure whereby a cutting blade may be offset laterally or radially from its support and may also depend sufficiently to provide ample clearance for the cutting edges.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is an elevation of a drilling device equipped with blades constructed in accordance with this invention, portions being illustrated in section,

Fig. 2 is a sectional detail of the clamping portion of the device,

Fig. 3 is a cross sectional view taken on the line 3-3 of Fig. 2,

Fig. 4 is a perspective view of the improved blade, and

Fig. 5 is a cross sectional detail of the same.

In the drawings the numeral 10 designates a tubular member or upper section which

may be suitably formed of a piece of pipe, a tool joint or other material. At the upper end of the member 10 a screw threaded socket 11 is provided for connecting the device with a line of drill pipe. The lower end of the member 10 is flared or beveled inwardly to form an inclined or undercut seat 14, and the bore of the member immediately above the seat is screw threaded to receive the upper screw threaded end of a tubular support 15. The support has an annular collar 16 preferably integral therewith, and provided at its upper edge with a downwardly inclined or undercut annular seat 17. It will be seen that the seats 14 and 17 diverge and form a dove-tail socket therebetween. A threaded nipple 24 depends from the support immediately below the collar. A tubular extension or pipe 23 is screwed onto the nipple and is screwed into a collar 25 at its lower end which may receive a drilling tool 26 of any character. The support 15, collar 16, nipple 24 and extension 23 may be designated as the lower section of the device. These parts are fully and amply described in the aforesaid Letters Patent and are referred to herein merely to explain the present invention.

The invention resides in cutting blades 18, each having its upper portion formed integral with a shank 19 which has an inner arcuate surface or face 20, conforming to the contour of the member 15. The blade proper projects laterally and substantially radially from the shank. The blades are preferably, but not necessarily, attached to the centers of the shanks so as to provide a substantial construction and resist torsional strain. The blades each have a sloping shoulder 21 which prevents catching in the casing when the device is elevated in the well. The upper and lower ends of the shanks are beveled to correspond with the inclination of the seats 14 and 17, and to engage therein.

The shanks rest on the seat 17 and by rotating the member 10, its seat 14 is brought to bear on the upper edges of the shanks, whereby the latter are clamped in place. The member 10 constitutes a clamping element and the shanks preferably completely surround the member 15; however, it is not necessary that the shanks completely surround the member 15 as they may be suitably spaced apart and the spaces filled in in a suitable manner. It is important, how-

ever, that the shank be prevented from creeping or moving circumferentially of the support 15. By unscrewing the member 10 the blades may be easily removed for sharpening or other purposes. The blades overhang the collar 16 and depend at the side thereof, so that their lower cutting edges 22 are positioned below said collar. The cutting edges or cutters 22, are formed by beveling and reducing the blades, whereby the cutters project in advance of the blade proper. It will be noticed that the upper portion of each cutter is reduced upwardly from a shoulder 18' whereby the blade is given ample clearance to work efficiently.

It is to be understood, however, that the cutters of the blades may assume any desired shape, and the invention is not to be limited to any particular shape or inclination. It is pointed out that the blades are substantially equidistant from the center of the member 15, so as to drill a hole concentric to the device. Particular stress is placed upon the structure of the blade and the ample bearing afforded by its shank 19. Each shank is supported on the seat 17 and any upward thrust is sustained by the seat 14. The arcuate face 20 gives an ample bearing against the support 15. The blades are securely fastened and cannot possibly have any play on their support; however the blades may be readily and easily removed.

In using the device with a rotary drilling machine, water under pressure is supplied to the member 10 and passed down through the bore of the support 15 to the extension 23 from which it is conveyed to the usual ports 26' in the drilling bits. In some formations it will be necessary to supply water to the cutters 22 to cleanse the same. A plurality of downwardly directed ports 27 extend through the collar 16 from the bore of the member 15 to the lower edge of said collar so as to direct jets of water on the cutters. When it is not desired to use said ports they may be closed by screwing plugs 28 thereinto, the same to be removed when desired. The device may be constructed without the ports 27.

It is obvious that a drilling device of this character will bore the well much faster, thus saving time and labor. The bit 26 or other tool will make a rat tail or other smaller hole in advance and will leave merely the rim or ledge for the blades to cut. It is equally plain that the cutters 22 may be

given any desired angularity so as to cut either a right angular shoulder or an inclined shoulder. By means of the advanced drill the device is constantly centered and caused to axially rotate, thus obviating swinging, whereby enlarging of the hole is prevented.

Various changes may be made in the construction of the blade and it is to be understood that the invention is not to be limited to the exact supporting structure herein shown. The invention is not limited to a plurality of blades and may be used in connection with drilling devices or tools employing only one blade. Various other changes and modifications may be made without departing from the spirit of the invention.

What we claim, is:

1. A blade for well drilling devices including, a shank having its upper and lower ends beveled to engage a retaining socket, and a blade member extending laterally from the shank and depending therefrom, the lower end of the member being reduced and provided with a transverse cutter.

2. A blade for well drilling devices including, a blade member formed upon a curved shank, said blade member being offset laterally and outwardly with relation to the curved shank and depending below the same, said blade member being provided at its lower end with a cutter.

3. A blade for well drilling devices including, a shank, a blade member disposed along the outer side of the shank with the shank projecting beyond the opposite sides of the blade member, said blade member being integral with and projecting laterally beyond the shank and extending downwardly beyond the shank, said blade member being provided near its lower end with a cutter.

4. A blade for well drilling devices, including, a shank, a blade member formed integral with the shank and projecting radially beyond the same, said blade member extending downwardly below the shank and having a cutter at its forward end, said blade member being laterally reduced from a point near and spaced from the edge of the cutter to the upper end of the blade member.

In testimony whereof we affix our signatures:

PRIMUS W. SMITH.
JOHN J. BOOKHOUT.
